United States Patent Office

Des. 208,155
Patented July 25, 1967

208,155

SADDLE STAND

Arthur H. Swanson, P.O. Box 76, and James A. Stark,
69 Rose Place, both of Clarendon Hills, Ill. 60514

Filed July 14, 1966, Ser. No. 3,136

Term of patent 14 years

(Cl. D38—1)

The figure is a perspective view of a saddle stand showing our new design. The sides not shown in the drawing are substantially the same as the sides shown.

We claim:

The ornamental design for a saddle stand, substantially as shown and described.
